COMBINED FOOD AND BEVERAGE VENDING STAND

Edwin G. Lindgren, La Grange, Ill., assignor to Servarround Corporation, Lemont, Ill., a corporation of Illinois

Filed Mar. 1, 1960, Ser. No. 59,573

Term of patent 14 years

(Cl. D13—1)

Des 189,416

Fig. 2.

Fig. 3.

The sides of the stand not shown in the drawings are substantially like the sides shown.

I claim:

The ornamental design for a combined food and beverage vending stand, substantially as shown and described.
